UNITED STATES PATENT OFFICE.

HARRY E. MILLER AND JOHN H. JAYNE, OF MONMOUTH, ILLINOIS.

HOG-TROUGH.

1,378,263.

Specification of Letters Patent.

Patented May 17, 1921.

Application filed May 18, 1917. Serial No. 169,399.

To all whom it may concern:

Be it known that we, HARRY E. MILLER and JOHN H. JAYNE, citizens of the United States, residing at Monmouth, in the county 5 of Warren and State of Illinois, have invented certain new and useful Improvements in Hog-Troughs, of which the following is a specification.

Our invention relates to improvements in 10 the construction of troughs especially designed for feeding hogs.

One of the main objects of our invention is to provide a trough having the body portion formed from a single sheet of metal and 15 stamped or bent into the desired shape and provided with end portions which maintain the trough in stable position and are of great strength and rigidity.

In the accompanying drawings, Figure 1 20 is a perspective view of a trough embodying our invention; Fig. 2 is a longitudinal section of the same; and Fig. 3 is a fragmentary top plan view of one end of the body portion.

The body portion 1 is stamped or bent 25 from a single sheet of metal, substantially semi-cylindrical in cross-section forming a horizontally disposed trough or channel, with marginal flanges 2, the ends 4 being 30 bent up substantially perpendicular to the bottom of the trough to form vertical walls and curved or arched inwardly as shown. The end supports are provided with a top plate portion 6, having an arcuate inner 35 edge flanged at 7 to fit tightly over the upper edge of the inwardly curved end walls 4, and having downwardly inclined supporting portions 8, provided with bottom flanges 9.

The flanges 2 are secured to the top plates 40 6 by means of bolts 10, which pass through the bottom flanges 9, and constitute tie-rods between the plates 6 and the flanges 9. The bolts or tie-rods 10 are incased by sleeves 45 or pipes 12 which serve as compression members of the truss formed by the parts of bent end plate 6, 7, and 9, this construction producing an exceedingly rigid brace for the ends of the trough which is able to withstand 50 the onslights of the most powerful hogs and all of the rough usage to which it may be subjected in the field, such as the weight of a loaded wagon that may chance to pass over it. Again by striking up the metal of 55 the curved end walls 4 until they are substantially vertical and perpendicular to the

top plate portions 6, they are in a position to afford the greatest resistance to compression strains tending to crush or bend the ends of the trough. These vertical end walls 60 coöperate, therefore, with the bolted trussed reinforcement in resisting crushing strains. Any strains tending to force the plate portions 8 inwardly are resisted by the compression sleeve members 9, while any outward lateral strains on the plate portions 65 8 are resisted by the tension tie-rods 10.

We have described in detail the particular construction illustrated in the accompanying drawings for the purpose of clearly 70 disclosing one embodiment of our trussed end construction but it will be understood that changes may be made within the scope of our claims and without departing from our invention.

We claim:

1. A trough, comprising a body portion formed from a single sheet of metal bent to provide a horizontally disposed channel portion and end walls, said end walls being 80 inwardly convex substantially throughout their width and being substantially perpendicular to the bottom of the trough and vertical when the trough is in normal position, and end plates each having a top portion extending over the adjacent curved end wall and a downwardly extending support rigidly braced with relation to said body portion.

2. A trough comprising in combination a body portion formed from a single sheet of material with its side walls curved upwardly and outwardly and having laterally directed and longitudinally extending flanges formed at the upper edge of each side, said body portion also having substantially vertical end walls curved inwardly from their outer extremities and toward each other, a support secured to each end of the body portion having a top plate portion extending over the curved end wall and the adjacent ends of the side walls of the body portion, and extending downwardly therefrom and rigidly braced at each side to hold the end supports in position relative to the body portion for 90 100 the purposes stated.

3. A trough comprising in combination a body portion formed from a single sheet of material with its side walls curved upwardly and outwardly and having laterally directed and longitudinally extending flanges formed at the upper edge of each side, said body 110

portion also having substantially vertical end walls curved inwardly from their outer extremities and toward each other, end supports each having an inwardly extending 5 plate portion overlapping the adjacent end wall and the adjacent ends of the side walls of the body portion and extending downwardly therefrom and a flange at the bottom of each of the end supports, each end 10 support being braced at each side thereof to hold them rigidly in position relative to the body portion substantially as and for the purposes stated.

4. A trough comprising in combination a 15 body portion formed from a single sheet of material with its side walls curved upwardly and outwardly, laterally directed and longitudinally extending flanges formed at the upper edge of each side, said body portion 20 also having substantially vertical end walls curved inwardly from their outer extremities and toward each other, end supports each having a flange portion overlapping the adjacent end wall and the adjacent ends of the 25 side walls of the body portion and extending downwardly therefrom, and braces rigidly connecting said longitudinally extending flanges and said end supports adjacent each end of the trough so that the end supports 30 are rigidly braced with respect to the body portion of the trough.

5. A trough, comprising a horizontally-disposed channel member having formed integral therewith at each end an inwardly curved end wall which is substantially vertical when the trough is in normal position, and a support secured to each end having 35 a top plate portion extending over the curved end wall and conforming thereto, an upright portion provided with an inwardly directed flange at its base and a bolt 40 connecting said top plate and said base flange.

6. A trough, comprising a horizontally-disposed channel member having formed integral therewith at each end an inwardly curved end wall which is substantially vertical when the trough is in normal position, and a support secured to each end having a 45 top plate portion extending over the curved end wall and conforming thereto, an upright portion provided with an inwardly di-

rected flange at its base, a bolt connecting said top plate and said base flange, and a compression member sleeved about said bolt. 55

7. A trough, comprising a horizontally-disposed channel member having formed integral therewith at each end an inwardly curved end wall which is substantially vertical when the trough is in normal position, 60 and a support secured to each end having a top plate portion extending over the curved end wall and having a depending flange extending over the edge thereof, an upright portion extending downwardly and inwardly therefrom and provided with a flange at its base, and a bolt connecting said flange and said top plate. 65

8. A device of the character described including a trough body, supporting legs 70 therefor arranged in pairs at the extremities of the trough body, and supports for the said legs extending between the legs of the respective pairs thereof and overlying the upper edges of the end walls of the trough 75 body, the said supports acting to brace the legs against displacement longitudinally with respect to the trough body.

9. A device of the character described including a trough body, supporting legs 80 therefor, and supports extending between the legs at the respective extremities of the trough body, the said supports being each formed from a single sheet of material bent to provide a cap plate and being arranged 85 with the said plates overlying the end walls of the trough body with the said supports inclining from the said plates to the lower extremities of the said legs.

10. A device of the character described 90 including a trough body having end walls curved transversely of the trough, supporting legs for the trough body, and supports connected with and extending between the lower ends of the legs at the extremities of 95 the trough body, the said supports being secured at their upper extremities to the body of the trough and inclined from the upper margins of said end walls inwardly therebeneath. 100

In testimony whereof we affix our signatures.

HARRY E. MILLER.
JOHN H. JAYNE.
